UNITED STATES PATENT OFFICE.

WALTER G. CAMPBELL, OF MARYSVILLE, OHIO.

DESIGN FOR A CLOCK.

47,946.

Specification for Design.

Patented Oct. 12, 1915.

Application filed June 18, 1915. Serial No. 34,932. Term of patent 14 years.

To all whom it may concern:

Be it known that I, WALTER G. CAMPBELL, a citizen of the United States, residing at Marysville, in the county of Union and State of Ohio, have invented a new, original, and ornamental Design for Clocks, of which the following is a specification, reference being had to the accompanying drawing, forming a part thereof.

Figure 1 is a front elevation of a clock,

showing my new design; and Fig. 2 is a side elevation. Fig. 3 is a top plan view.

I claim:

The ornamental design for a clock, as shown.

WALTER G. CAMPBELL.

Witnesses:

E. C. PRIDY,

E. S. BOUN.
